UNITED STATES PATENT OFFICE.

GLENN B. WARREN, OF SCHENECTADY, NEW YORK, ASSIGNOR TO GENERAL ELECTRIC COMPANY, A CORPORATION OF NEW YORK.

LOCOMOTIVE.

Application filed December 30, 1925. Serial No. 78,430.

The present invention relates to locomotives and especially to locomotives wherein the drive includes a low pressure elastic fluid turbine which operates condensing.

5 In connection with such locomotives, the power required to drive the auxiliaries, such as the circulating pump for the feed water, the fans for the air cooling chamber, the exhaust gas blower and the like, is comparatively high. In fact, the amount of power 10 for the auxiliaries is so large in proportion to the total power developed, that the overall efficiency of the locomotive is very seriously affected by the efficiency of the drive 15 for the auxiliaries.

The object of my invention is to provide an improved construction and arrangement of driving means for a locomotive embodying a low pressure turbine, which driving 20 means will have an overall efficiency higher than systems now in use, and for a consideration of what I believe to be novel and my invention, attention is directed to the following specification and the claims appended thereto.

According to my invention, I divide the driving means proper for the locomotive into two units, a high pressure unit which may be an engine of either the reciprocating 30 or rotary type, such as an elastic fluid turbine, and a low pressure unit in the form of a condensing turbine. For driving the auxiliaries, I then provide a single unit in the form of a low pressure turbine or a low 35 pressure turbo-generator set, the generator of the set furnishing electric current to motor driven auxiliaries. The turbine of the low pressure turbo-generator set is operated by exhaust elastic fluid from the high pressure driving unit and is arranged preferably 40 in series with the low pressure turbine as this arrangement possesses advantages of a substantial order as is hereinafter pointed out. However, it may be arranged in parallel with the low pressure turbine.

By the above described arrangement the turbine or the turbo-generator set for furnishing power to drive the auxiliaries becomes fairly large, that is the volume of 45 elastic fluid handled becomes quite large. At the same time, it is required to operate over a comparatively small pressure range. As a result it lends itself to being built to give much higher efficiency than would be 50 the case otherwise, as is well understood by

those skilled in the art of turbine construction.

In the drawing, Fig. 1 is a diagrammatic view of a locomotive embodying my invention, and Figs. 2 and 3 are similar views of 60 modifications.

Referring to Fig. 1, the locomotive is shown as comprising a primary section 1 and a secondary section 2. Primary section 1 is driven by a reciprocating engine 3 65 which may be a usual form of reciprocating engine driven machine, it being understood that the engine comprises cylinders upon both sides of the locomotive. Secondary section 2 is driven by a low pressure condens- 70 ing turbine 4 through suitable gearing 5 or by other suitable means. 5^a indicates a condenser for turbine 4, and 6 a cooler for the circulating water for the condenser. Mounted at the front end of primary section 75 1 is a turbo-generator set 7 which furnishes power to drive all the auxiliaries. It is located as close as possible to the cylinders of engine 3 and the admission opening of the turbine is connected to receive exhaust elastic 80 fluid from engine 3 by suitable conduit means 8. Conduit means 8 is made as short and as small as possible in order to reduce its receiver capacity to a minimum. The exhaust opening of the turbine of the turbo-generator set is connected by a conduit 9 to the admission end of low pressure turbine 4. 10 is a by-pass conduit controlled by a valve 11. Valve 11 is normally closed but may be 85 opened to connect conduit 8 directly to conduit 9, thus by-passing elastic fluid around turbo-generator set 7. The auxiliaries of the locomotive are not shown in the drawing, a showing of said auxiliaries being unnecessary for an understanding of the invention. 90

With the above-described arrangement, the boiler of the locomotive generates elastic fluid and this is supplied to engine 3 in the usual manner. From engine 3 the exhaust 100 elastic fluid flows through conduit means 8 to the turbine of turbo-generator set 7 and from thence through conduit 9 to low pressure turbine 4. The turbine of turbo-generator set 7 thus operates in series with low 105 pressure turbine 4.

As pointed out above, the turbine of turbo-generator set 7 is placed as close as possible to the cylinders of engine 3 and conduit means 8 is made as short and of as small ca- 110

pacity as possible. This is a thing of substantial importance, and for the following reasons:—

As is well known, the exhaust from a reciprocating engine comes in a series of "puffs". This is due to the fact that at the moment of the exhaust valve opening a considerable pressure exists in the cylinders on account of the incomplete expansion of the elastic fluid to the back pressure at which the engine is working. The pressure of the elastic fluid in the cylinder at the moment of the exhaust valve opening is, of course, a function of the incompleteness of the expansion which in turn is a function of the lateness of the "cutoff". Due to this pressure at the moment of exhaust valve opening, there is a considerable amount of energy stored in the steam over and above that stored in the steam when it has been exhausted to the uniform back pressure against which the engine is working. The amount of such energy stored in this exhaust steam depends upon the pressure in the cylinders at the time of the exhaust valve opening, which, as mentioned above, depends upon the lateness of the "cutoff". For example, at 80% cutoff, approximately 50% of the energy available in the elastic fluid from the initial pressure to the back pressure is still unused by the cylinders at the time the exhaust valve is opened. This means that there is as much energy available in the elastic fluid at the time the exhaust valve is opened as the cylinders have used.

An ordinary locomotive reciprocating engine operates at from 40% to 85% "cutoff", depending upon the draw bar pull, and this means that there is available in the exhaust elastic fluid down to the back pressure against which the engine is working, energy equivalent to from 25% to 105% of the power delivered by the locomotive.

By placing the turbine of turbo-generator set 7 directly adjacent to cylinders 3 and connecting it to them by conduit means having a minimum receiver capacity, I am enabled to utilize a considerable amount of the energy of the elastic fluid which otherwise would be lost in the expansion of the elastic fluid from the cylinder pressure down to the back pressure or receiver pressure. In other words, by my arrangement I am enabled to utilize the "puffs" of elastic fluid from the cylinder in operating the turbo-generator set. In fact, it becomes readily possible by this arrangement to utilize in the turbo-generator set 7 energy of the elastic fluid which would otherwise be lost completely. It may be in some cases that the amount of this energy which is thus recovered will be sufficient to supply all of the auxiliary power. This means, therefore, that the turbo-generator set 7 and so the auxiliaries may be operated without actually decreasing the

power which the elastic fluid would deliver to the engine 3 and turbine 4 even were the turbo-generator set 7 not present. I am thus enabled to make a very substantial gain in the overall efficiency of the locomotive.

In Fig. 2 I have shown a modification of my invention wherein the primary section 12 of the locomotive is driven by the elastic fluid turbine 13, suitably connected to the driving wheels of the locomotive. In the present instance it is shown geared, as indicated at 14. In this figure, 15 indicates the secondary section of the locomotive; 16 the low pressure turbine for driving it; 17 the condenser for turbine 16, and 18 the cooler for the circulating water for condenser 17. In this arrangement the turbo-generator set 19, corresponding to the turbo-generator set 7 of Fig. 1, which furnishes power for the auxiliaries, is mounted in the present instance on the secondary section 15 of the locomotive and is connected in series with low pressure turbine 16. 20 indicates a conduit through which elastic fluid is supplied from the boiler of the locomotive to the turbine 13. 21 indicates a conduit which conveys the exhaust fluid from turbine 13 to the turbine of turbo-generator set 19. The exhaust elastic fluid from the turbine of turbo-generator set 19 is conveyed to low pressure turbine 16 by conduit 22. 23 is a by-pass conduit controlled by valve 24 and which may be utilized to by-pass elastic fluid around the turbine of turbo-generator set 19, if desired. Valve 24 corresponds to valve 11 of Fig. 1.

In Fig. 3, I have shown an arrangement similar to that shown in Fig. 2, except that the turbo-generator set for driving the auxiliaries is connected in parallel with the low pressure turbine rather than in series therewith, as is shown in Fig. 2. In Fig. 3 reference numerals the same as those used in Fig. 2, with the exponent "a" added have been applied to corresponding parts. The exhaust from high pressure turbine 13^a is conveyed through conduit 21^a to a point adjacent to the turbo-generator set 19^a. Here two branches are provided, a branch 25 which conveys elastic fluid to the turbine of turbo-generator set 19^a and a branch 26 which conveys elastic fluid to low pressure turbine 16^a. The exhaust from the turbine of turbo-generator set 19^a is conveyed by a conduit 27 to condenser 17^a. In conduit 25 is a valve 28 for regulating the flow of elastic fluid through such conduit.

In connection with each of the arrangements shown there is obtained the advantage that the power supplied to the turbo-generator set utilized for operating the auxiliaries varies directly with the power supplied to the engines which propel the locomotive. This is a most advantageous feature in that

it renders the turbo-generator set practically self-governing, the power delivered by it increasing and decreasing directly with increase and decrease in the demand on the locomotive. Furthermore, the auxiliaries will automatically stop and start with the stopping and starting of the main locomotive and greatly reduce the stand-by losses of the complete unit.

10. In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

15. What I claim as new and desire to secure by Letters Patent of the United States is:—

20. 1. The combination with a locomotive comprising a high pressure engine, a low pressure condensing turbine, and auxiliaries, of a turbo-generator set for supplying power to drive the auxiliaries, said turbo-generator set and low pressure turbine being operated by exhaust elastic fluid from the high pressure engine.

2. The combination with a locomotive comprising a high pressure engine, a low pressure condensing turbine, and auxiliaries, of a turbo-generator set for supplying power to drive the auxiliaries, said turbo generator

set and said low pressure turbine being connected in series to the exhaust end of the high pressure engine.

35

3. The combination with a locomotive comprising a high pressure reciprocating engine, a low pressure turbine, and auxiliaries, of a turbo-generator set for supplying power to drive the auxiliaries, said turbo-generator set being located directly adjacent to the cylinders of the reciprocating engine and having the inlet of its turbine connected to receive the exhaust from the engine cylinders, the exhaust of such turbine being connected to the inlet of the low pressure turbine.

40

4. A locomotive comprising a high pressure engine, a low pressure turbine connected in series with it, and auxiliaries, characterized by the fact that the auxiliaries are driven by power supplied by an independent low pressure turbine operated by elastic fluid from the high pressure engine.

45

5. A locomotive comprising a high pressure engine, a low pressure turbine connected in series with it, and auxiliaries, characterized by the fact that the auxiliaries are driven by power supplied by an independent low pressure turbine operated in series with the first named low pressure turbine.

55

In witness whereof, I have hereunto set my hand this 29th day of December, 1925.

GLENN B. WARREN.
